UNITED STATES PATENT OFFICE.

WILLIAM E. WOODARD, OF SCHENECTADY, NEW YORK, ASSIGNOR TO AMERICAN LOCOMOTIVE COMPANY, OF NEW YORK, N. Y., A CORPORATION OF NEW YORK.

CAR-TRUCK.

No. 918,807.

Specification of Letters Patent. Patented April 20, 1909.

Application filed June 5, 1908. Serial No. 436,772.

To all whom it may concern:

Be it known that I, WILLIAM E. WOODARD, of Schenectady, in the county of Schenectady and State of New York, have invented a certain new and useful Improvement 5 in Car-Trucks, of which improvement the following is a specification.

My invention relates to car trucks of the general class or type in which the weight applied to the truck is supported thereon by a bolster which has the capacity of lateral as well as vertical movement, and is suspended by swing hangers from the relatively fixed members of the truck frame.

15 The object of my invention is to provide means, of simple and inexpensive construction and ready applicability in car trucks of the constructions known and approved in present practice, whereby the angle of the swing hangers and the degree of lateral movement of the bolster may be varied and adjusted and the levels of the spring plank and bolster be varied as desired.

The improvement claimed is hereinafter 25 fully set forth.

In the accompanying drawings: Figure 1 is a side view, partly in vertical longitudinal section on the line *a a* of Fig. 2, of a car truck, illustrating an application of my invention; 30 Fig. 2, a transverse section through the same, on the line *b b* of Fig. 2; Fig. 3, a side view, partly in section, of one of the swing hangers and its connections, and; Fig. 4, an end view, partly in section, of a pair of bolster springs, 35 showing also a pair of swing hangers and connections.

My invention is herein exemplified as applied in a four wheel car truck, the frame of which comprises two side members, 1, and 40 transoms, 2, connecting the side members on opposite sides of the central transverse plane of the truck. The side frames are provided with pedestals, 3, in which are fitted the axle boxes, 4, of a pair of axles, 5, on which are 45 secured the wheels, 6. The weight of the car carried by the truck is supported thereon by a swing or lateral motion bolster, 7, which is supported, through the intermediation of pairs of bolster springs, 8, adjacent to its 50 ends, on a spring plank, 9, suspended from the transoms, 2, of the truck frame, by pairs of swing hangers, 10, the upper ends of which are coupled to upper swing hanger pivots, 11, fixed on the transoms, the lower ends of 55 which swing hangers are, in the construc-

tions heretofore known and used, coupled to lower spring hanger pivots on the spring plank.

In the practice of my invention, a swing hanger bearing, 12, having a plurality of segmental recesses, 12^a, on its lower sides, is secured to the spring plank, 9, at each of its ends, said swing hanger bearings also serving as seats for the lower members of the pairs of bolster springs, 8. The spring hanger seats 60 being permanently fixed to the spring plank, perform their functions in the same manner as if integral therewith, as they might be made if desired, but, for convenience and economy of construction they are preferably 65 made separate pieces and riveted or bolted to the spring plank. Vertical slots, 10^a, are formed in the swing hangers near their lower ends, and a cross bar or gib, 13, the upper edge of which is curved segmentally, in substantial correspondence with the curvature 70 of the recesses, 12^a, of the spring hanger bearings, and which is provided with downwardly turned end lips or projections, 13^a, to prevent lateral displacement of the swing hangers, is 75 fitted in the slots of each pair of swing hangers, 10, and interposed between the same and one of the segmental recesses, 12^a, of the adjacent swing hanger bearing, the curved upper edge of the gib abutting against said 80 recess.

As shown in Fig. 4, the slots, 10^a, of the swing hangers, are of greater depth than the gibs, 13, thereby leaving open spaces above 85 the tops of the gibs and permitting the substitution of gibs of different depth when it is desired to vary the vertical relation of the hangers and spring plank.

It will be seen that by locating the gibs, 13, in one or another of the recesses of the swing hanger bearings, the vertical angle of the swing hangers may be varied as desired and the resistance of the bolster to lateral motion be correspondingly increased or diminished. This variation is effected without any perceptible change of the level of the spring plank. Vertical adjustment of the spring plank and bolster may also be effected by using gibs of greater or less depth as desired, or by inserting one or more liners 100 between the spring plank and the swing hanger bearing.

I claim as my invention and desire to secure by Letters Patent:

1. In a car truck, the combination of a 110

truck frame, a swing or lateral motion bolster, swing hangers by which said bolster is suspended from the frame, and means for varying and adjusting the angle or inclination of the swing hangers relatively to the frame, without perceptible change of the vertical relation of the members.

2. In a car truck, the combination of a truck frame, a spring plank, swing hangers by which said spring plank is suspended from the frame, a swing or lateral motion bolster which is spring supported on the spring plank, and means for varying and adjusting the angle or inclination of the swing hangers relatively to the frame, without perceptible change of the vertical relation of the bolster and spring plank.

3. In a car truck, the combination of a truck frame, a spring plank, swing hangers by which said spring plank is suspended from the frame, a swing or lateral motion bolster which is spring supported on the spring plank, and supporting members for the spring plank which fit in slots of greater depth in the spring hangers, whereby capability of variation of the vertical relation between the spring hangers and the spring plank is provided for.

4. In a car truck, the combination of a truck frame, a spring plank, swing hangers pivotally supported on the frame at their upper ends and having vertical slots adjacent to their lower ends, gibs, of less depth than the vertical slots, said gibs passing through and bearing on the lower ends of said slots and on the lower side of the spring plank, and a swing or lateral motion bolster which is spring supported on the spring plank.

5. In a car truck, the combination of a truck frame, a spring plank, swing hangers pivotally supported on the frame at their upper ends and having vertical slots adjacent to their lower ends, a swing hanger bearing having a series of segmental recesses on its lower side and fixed to the spring plank, gibs passing through and bearing on the lower ends of said slots and on a recess of the swing hanger bearing, and a swing or lateral motion bolster which is spring supported on the spring plank.

WILLIAM E. WOODARD.
